UNITED STATES PATENT OFFICE

JAMES M. HOWE, OF CLEVELAND HEIGHTS, OHIO, ASSIGNOR TO THE MURRAY PRODUCTS COMPANY, OF CLEVELAND, OHIO, A CORPORATION OF MICHIGAN

VEHICLE BODY

Application filed September 6, 1924. Serial No. 736,226.

This invention is concerned with vehicles and has for its general object the provision of a spring-suspended vehicle body construction having a chassis built into and comprising part of the body of the vehicle.

A further object of my invention is the provision of a pressed metal body for a toy vehicle of the foot-propelled type, the body being formed to present the usual streamline design but comprising a light, rigid, open bottom construction to which a full spring suspension may be directly attached and which involves the use of only a minimum number of parts.

Other objects of my invention will hereinafter be set forth in the following description referring to the accompanying drawings illustrating a preferred form thereof. The essential characteristics are summarized in the claims.

In the drawings, Fig. 1 is a plan view of the body of a toy vehicle constructed in accordance with the objects of my invention; Fig. 2 is a longitudinal cross-sectional elevation taken through the body; Fig. 3 is a cross-sectional plan view taken through the rear portion of the body substantially along the line 3—3 of Fig. 2; Fig. 4 is a cross-sectional elevation taken along the line 4—4 of Fig. 1; Fig. 5 is a front end elevation of the body with the front or radiator panel omitted; Fig. 6 is a plan view of the rear of a body modified whereby the rear is formed by extensions of the side members joined along the middle of the body; and Fig. 7 is a transverse cross-sectional view taken along the line 7—7 of Fig. 6.

It has been the practice heretofore to construct the bodies of toy vehicles, particularly those toys representative of automobiles, of wooden frames and light sheet metal panels nailed or otherwise attached to the wooden frames. My invention contemplates the construction of a toy automobile body formed throughout of pressed metal parts and reinforced in such a manner that the lower portion of the body may comprise a chassis, thereby permitting incorporation of a full spring suspension for the body as illustrated

in my prior application Serial No. 641,616, filed May 26, 1923, on "a vehicle".

As shown in the drawings, the present embodiment of my invention is comprised of two longitudinal body members 9 and 10 which are complementary in contour and form the hood, the cowl and the side walls of the body. These members may be joined along the hood and cowl portions thereof, by an inverted seam formed by inwardly extending abutting flanges 11 and 12 as shown in Fig. 5. The front of the body may be completed by a flanged panel member 13 riveted or otherwise secured to the front edges of the body members 9 and 10. The rear of the body is completed by a sloping panel member 14 joined to the side portions of the members 9 and 10 and to a transverse reinforcement in the nature of a seat structure as will hereinafter be described.

To reinforce the side portions of the body members 9 and 10 whereby the body may be provided with a built-in chassis construction, longitudinal sill members 16 and 17 which may be L-shaped in cross section, are disposed to engage inwardly flanged portions 19 and 20 of the body members 9 and 10 respectively. Horizontally disposed reinforcing plates 22 and 23 may extend along the sill members 16 and 17 to stiffen the sill construction at the place of attachment for spring bracket members 25 and 26 formed of flat metal of a T-shape as shown in Fig. 4. The latter members may be secured to the body members 9 and 10 by any suitable means such as rivets 28 extending through the side walls of the body and vertically extending portions of the bracket members 25 and 26 and through the sill members 16 and 17 respectively. To these brackets may be attached suitable spring connectors 20^a and 20^b preferably in the form of U-clips.

The transverse reinforcing of the body is effected by the seat structure as shown in Figs. 1, 2 and 4 which may comprise a bottom seat member 30 formed of sheet metal suitably ribbed and flanged as shown in Figs. 2 and 3 to afford attachment to an arcuately formed back member 31. The back member may ex-

tend the width of the body and have the top edge thereof merge with the contour of the top edges of the side members 9 and 10 whereby a suitable reinforcing bead 32 may be formed about a wire cord 33, thus affording a convenient manner of finishing the exposed top edges of the body members and the seat member. The back body member 14, of course, may have the forward edge thereof shaped to closely fit the back of the member 31.

The bottom seat member, as shown in Fig. 4, is provided with a downwardly extending portion 36 relieved at its center to provide clearance for propelling members (not shown). The seat portion 36 is also provided with a stiffening flange 37 which may extend into and be secured to the sill structure as shown in Fig. 4.

The forward end of the body as stated is reinforced by the flanged radiator panel 13 secured to the front edges of the body members 9 and 10 and also by a transversely extending bracket member 40 secured to the sills 25 and comprising a support for a pedal suspension and steering gear not shown. The body may be also reinforced by a transverse member 41 suitably shaped and flanged to afford rigidity to the body and to comprise in imitation of a dash or instrument board disposed immediately adjacent the edges of the body top opening.

If desired, a package compartment 42 may be provided at the rear of the vehicle body. This compartment may be formed by a pressed metal box structure 43 set into an opening formed in the rear member 14 and may be secured to the rear member by a supporting bracket 45, the opening in the body member 14 being flanged as shown at 46 in Fig. 2, whereby the box structure 43 may be more rigidly secured to the body, preferably by welding. The box structure may extend substantially the width of the body 45 whereby it may comprise a transverse bracing or reinforcing for the rear of the body as shown in Figs. 1 and 2. A cover 50 is provided to close the compartment and may comprise a flanged steel plate and a hinge member 51 secured to the inner face of the body member 14 and to the plate member.

The lower rear portion of the body members 9 and 10 and the rear closure 14 which are not reinforced by the sill structure, hereinbefore described, may be suitably reinforced by flanging or by the bead structure 54 and 55, shown in Fig. 2 which may extend completely around the back edges of the body and forwardly to the rear ends of the sill structure.

The appearance of the body may be made to further conform to the general appearance of an automobile by the formation of louvers 58 formed in the hood portions of the side members 9 and 10 and by the formation of ribs 59

and 60 defining the hood and cowl portions of the body members. The side wall members may also be provided with ribs 61 and 62 located adjacent the seat structure to represent a side door.

In Figs. 6 and 7, I show a modified form of body construction whereby the rear portion of the body is formed entirely by extensions of the side members. In this construction the rear end portions of the side members may be formed in a manner similar to the formation of the front portions whereby they may be joined at the back along a median line. As shown in Fig. 6, the end portions 70 of the two members forming the body may be shaped to present a sloped appearance, the slope of the portions 70 extending from the seat back 32 with the top edges formed by curved portions 71. The back edge may be curved to blend with the side edge radii if desired. As shown in Fig. 7, inwardly extending flanges 73 are formed along the abutting edges of the back portions of the two members whereby the back of the members may be joined in the same manner as the front thereof. While introducing such curved surfaces into the designs of the body members would seem to complicate the manufacture thereof, I find that by first forming the body in halves and completing the assembly of the sill structure, brackets, etc., before imparting the final formation to the body members, the body may be quickly assembled. This is particularly true where the body comprises primarily but two metal members joined along a median line at the front and back of the body. Only the seat structure, the bracket 40 and dash piece 41 need thereafter be assembled in the body.

It will be readily seen that my invention affords an extraordinarily rigid but light construction for an all metal body formed of thin gauge sheet metal and that the nature of the construction is such that the vehicle may be provided with a full spring suspension attachable directly to the body. Also, that the construction is such as to further the general likeness to an automobile without detracting from the rigidity of the body. It is to be understood that if desired the body 105 could be constructed of three major pieces, namely, two side members joined at the front in the manner described and joined at the rear by a centrally disposed seam, the radiator comprising the third member of the body 110 and the sill construction and seat construction could be as shown and described herein.

It should also be noted that where the spring brackets are attached to the sill structures of the side walls, these walls are laterally braced by the built-in metallic seat structure at the rear brackets and by the pedal and steering column bracket at the front spring brackets, thus affording an open bottom body construction of extreme rigidity 125 130 135

and which will permit the use of a full longitudinal spring suspension for the body.

I claim:

1. A vehicle body comprising two pressed metal members forming the hood, cowl and side walls of the body, a pair of laterally flanged substantially straight sill members substantially uniform in cross section and secured to the lower edges of said side pressed metal members and terminating substantially midway between the ends of the said pressed metal members, said sill members diverging toward the rear of the body, a flanged seat member connecting the said pressed metal members above the rear ends of the sill members to substantially complete the body bracing, said pressed metal members converging toward the rear of the body from the ends of the sill members to form a stream line effect and means joining the rear ends of said pressed metal members rearwardly of the seat to close the body.
2. In a juvenile vehicle body, the combination of a pair of pressed metal side members forming the hood, cowl, and sides of the body, said members being joined together along the central vertical plane of the body, a sheet metal rear body member closing the back of the body and joined to the side members, and a seat structure comprising two pressed metal members, one being substantially vertically disposed and in abutting relation to the front edge of said back member with its ends curved into overlying relation to the side members and joined thereto, the other member of the seat structure being a sheet metal plate bent downwardly at its front edge for vertical support and extending rearwardly to form a seat bottom panel, the rear edge of the panel being flanged, and the flange being joined to the vertically disposed seat member, the ends of said plate being joined to said side members to serve as a tie between these members.
3. In a juvenile vehicle body, the combination of a pair of sheet metal side members having cowl and hood forming front portions extending inwardly and joined forwardly of the body, means joining the side members rearwardly of the body and forming a rear top closure, said means and side members forming a rounded seat opening, and a curved sheet metal seat back member disposed in abutting relation to said means and having its ends overlying and joined to the side members, the top edges of the side members, defining the forward portion of the seat opening, being curled to form a bead, and the said seat back member having its top edge similarly curled to form a bead, this bead merging with the bead formations of the side members.

In testimony whereof, I hereunto affix my signature.
